Patented April 25, 1905

UNITED STATES PATENT OFFICE.

RAYMOND BEARDSLEY GILCHRIST, OF NEWARK, NEW JERSEY.

DESIGN FOR A CORK-EXTRACTOR CASE.

SPECIFICATION forming part of Design No. 37,417, dated April 25, 1905.

Application filed March 27, 1905. Serial No. 252,428. Term of patent 7 years.

To all whom it may concern:

Be it known that I, RAYMOND BEARDSLEY GILCHRIST, a citizen of the United States, residing at Newark, in the county of Essex and State of New Jersey, have invented a new, original, and ornamental Design for Cork-Extractor Cases, of which the following is a specification, reference being had to the accompanying drawing, forming part thereof.

The figure is a perspective of a cork-extractor case, showing my new design.

I claim—

The ornamental design for a cork-extractor case, as shown.

RAYMOND BEARDSLEY GILCHRIST.

Witnesses:

MAE OSBORN,
ALFRED CLARKE.
